COMBINED FOUNTAIN BRUSH AND DENTAL CREAM HOLDER

Alfio L. Corbino, 3541 N. 6th Ave., Omaha, Nebr.

Filed Mar. 30, 1960, Ser. No. 59,950

Term of patent 14 years

(Cl. D9—2)

I claim:

The ornamental design for a combined fountain brush and dental cream holder, as shown.
